UNITED STATES PATENT OFFICE.

ADOLPH S. KLEIN, OF CLEVELAND, OHIO.

REFRIGERATOR.

1,216,576.

Specification of Letters Patent. Patented Feb. 20, 1917.

Application filed April 10, 1916. Serial No. 90,079.

To all whom it may concern:

Be it known that I, ADOLPH S. KLEIN, a citizen of the United States of America, residing at Cleveland, in the county of 5 Cuyahoga and State of Ohio, have invented certain new and useful Improvements in Refrigerators; and I hereby declare the following to be a full, clear, and exact description of the invention, such as will enable others skilled in the art to which it 10 pertains to make and use the same.

This invention relates to improvements in refrigerators designed for use by venders of perishable provisions.

15 One object of this invention is to provide simple and efficient means for controlling the supply of cold air to the provision-chamber.

Another object is to render a refrigerator 20 of the character indicated simple and durable in construction.

With these objects in view, and to the end of attaining any other advantage herein-after appearing, this invention consists in 25 certain features of construction, and combinations and relative arrangement of parts, hereinafter described in this specification, pointed out in the claim, and illustrated in the accompanying drawings.

30 In said drawings, Figure 1 is a vertical section of a refrigerator embodying my invention. Fig. 2 is an enlarged view of a portion of Fig. 1. Fig. 3 is a sectional view corresponding with Fig. 2, except that in 35 Fig. 3 the cold-air-deflectors are shown swung against the provision-supporting bars of the refrigerator. Fig. 4 is a substantially horizontal section taken at the upper longitudinal edges of said deflectors and next 40 above the hereinbefore mentioned drip-pans. Fig. 5 is a vertical section on line 5—5, Fig. 2. Figs. 2, 3, 4 and 5 are drawn on a larger scale than Fig. 1, and portions are broken away in the drawings to reduce their size.

45 My improved refrigerator is constructed internally in any approved manner to form an ice-chamber A within the upper portion of the refrigerator (see Figs. 1 and 2) and to form a provision-chamber B below the 50 ice-chamber and also to form passageways C (see Fig. 1) for conducting air from the upper ends of the outer portions of the provision-chamber to the upper portion of the ice-chamber.

55 Two suitably supported drip-pans D, which are arranged over opposite side por-

tions respectively of the provision-chamber and positioned to receive water dripping from opposite side portions of the ice-chamber, slope downwardly toward each other. 60

Under the central portion of the ice-chamber are sloping sections E arranged to drain water received thereby from the ice-chamber to the drip-pans D, and at the bottom of the ice-chamber over the drip-pans D and 65 sloping sections E are provided racks G for supporting ice to be supplied to the ice-chamber through a suitably applied door H shown in Fig. 1.

Each drip-pan D terminates at its lower 70 end in a substantially horizontally arranged trough d which extends from side to side and is rigid with said pan and spaced from the trough of the other drip-pan.

The refrigerator is provided at one end 75 of the provision-chamber with a doorway 6 shown in dotted lines, Fig. 4, and engaged by a suitably applied door b at which provisions are taken into and out of said chamber, and at the other end of the provision-chambers is provided a substantially 80 horizontally arranged trough I into which drain-pipes 7, with which the troughs d are provided, discharge, and a drain-pipe 8 is arranged to conduct water from the 85 trough I.

Two suitably supported bars K, adapted for use in supporting provisions within the provision-chamber, are arranged substantially horizontally in proximity to and extend 90 longitudinally of the troughs d. The troughs d and the bars K are substantially parallel. Passageways L, which are in communication with the ice-chamber, extend from over the drip-pans D to the bars K and are arranged 95 to conduct cold air from the lower end of the ice-chamber to the provision-chamber and discharge downwardly at said bars into the provision-chamber substantially centrally between opposite side walls of the 100 provision-chamber. Preferably the bars K are spaced laterally and arranged at opposite sides respectively of the upper end of the central portion of the provision-chamber.

Two laterally outwardly and downwardly 105 facing imperforate deflector-forming sections M are arranged between the discharging ends of the last-mentioned passageways L and extend longitudinally of the bars K, and the deflectors M converge downwardly 110 and are hinged at their upper longitudinal edges, as at m, to stationary bars 10 and ar-

ranged to swing in a vertical plane upon being rendered free to swing and removably secured together at their lower longitudinal edges as will hereinafter appear.

5 Preferably each deflector M (see Figs. 2 and 4) is provided at its outer side in proximity to its lower longitudinal edge with eyes 12 spaced longitudinally of said deflector and engaged by hooks 13 pivotally connected to the other deflector at the outer side of and in proximity to the lower longitudinal edge of the last-mentioned deflector and disengageable from said eyes.

10 At the outer side of each bar K is arranged a suitably supported substantially horizontal joist P which extends longitudinally of said bar which is supported in any approved manner from said joist. Said joist is provided at its top and outer side with a 15 rabbet 14 which extends longitudinally and from end to end of the joist, and the adjacent trough d is arranged within and seated on the bottom and extends longitudinally of said rabbet. At the outer side of and parallel with said joist P is a joist Q which is supported in any approved manner and extends above the bottom and longitudinally of the said rabbet, and consequently the inner side of the last-mentioned or outer joist 20 Q forms the outer side wall of the recess formed by said rabbet and the trough occupying said rabbet is confined laterally within said recess between the upright wall of said rabbet and inner side of said outer joist Q, and lateral displacement or distortion of 25 said trough is positively prevented.

30 Interposed between the outer side of the lower portion of each bar K and the adjacent joist P is a bar 15 attached in any approved manner to said joist.

35 In Figs. 1, 2 and 4 are shown hooks R 40 removably mounted on the bars K and instrumental in suspending provisions from said bar.

45 The deflectors M are preferably arranged as low at their lower longitudinal edges as the upper edges of the bars K so that the passage of cold air downwardly into the provision-chamber at said bars is insured.

50 In dotted lines Fig. 2 the deflectors M are shown detached from each other and hanging contiguously to the hooks R.

55 When the hooks R have been removed from the bars K, the deflectors M are free to be swung laterally against said bars, and Fig. 3 shows said deflectors thus swung and thereby closing the discharging ends of the

cold-air-conducting passageways L as required to conserve any ice which may be in the ice-chamber after removing all provisions from the provision-chamber.

60 I would here remark that the deflectors M are adequately held in their extreme outwardly swung position shown in Fig. 3 by placing the hooks 13 of said sections in engagement with eyes 16 with which the joists Q are provided, as shown in Fig. 3.

65 By the construction hereinbefore described it will be observed that the drip-pans and the connected troughs can be conveniently kept in a clean condition, that said troughs are adequately and inexpensively supported, that the cold-air-conducting passageways are caused to discharge vertically downwardly at the hooks R when the deflectors K 70 are in a vertically hanging position as shown in dotted lines Fig. 2, and that in said position of said deflectors and in their normal position shown in Figs. 1 and 4, and in solid lines Fig. 2 substantially all cold air 75 supplied to the provision-chamber is discharged downwardly into said chamber between the bars K.

80 What I claim is:—

85 In a refrigerator, an ice-chamber, a provision-chamber below the ice-chamber, passageways for conducting air from the upper ends of the outer portions of the provision-chamber to the upper portion of the ice-chamber, means for conducting off water 90 dripping from the ice-chamber, means at opposite sides respectively of the upper end of the central portion of the provision-chamber for supporting provisions, passageways arranged to conduct cold air from the ice-chamber and discharging at said provision-chamber, supporting means into the provision-chamber, and two laterally and downwardly facing deflectors arranged between the discharging ends of the last-mentioned passageways and converging downwardly and being hinged at their upper longitudinal edges and arranged to swing laterally in a vertical plane upon being rendered free to swing and detachably connected together at their 105 lower longitudinal edges.

100 In testimony whereof, I sign the foregoing specification, in the presence of two witnesses.

ADOLPH S. KLEIN.
